W. A. ERICKSEN,
SKATE FASTENER,
APPLICATION FILED SEPT. 6, 1918.

1,284,276.

Patented Nov. 12, 1918.

UNITED STATES PATENT OFFICE.

WILLIAM A. ERICKSEN, OF BROOKLYN, NEW YORK.

SKATE-FASTENER.

1,284,276.

Specification of Letters Patent. Patented Nov. 12, 1918.

Application filed September 6, 1918. Serial No. 252,903.

To all whom it may concern:

Be it known that I, WILLIAM A. ERICKSEN, a subject of the King of Norway, and a resident of the city of New York, borough 5 of Brooklyn, in the county of Kings and State of New York, have invented a new and Improved Skate-Fastener, of which the following is a full, clear, and exact description.

10 This invention relates to snow or ice skates, and has particular reference to means for easily, cheaply, and reliably securing or strapping such skates to the feet.

15 Among the objects of the invention, therefore, is to provide an improved means or method of strapping or binding a skate to a foot which involves the use of a light rope or cord, or a combination of such flexible connections which are easily applied to the 20 foot, and that are comfortable in practice.

With the foregoing and other objects in view the invention consists in the arrangement and combination of parts hereinafter described and claimed, and while the invention 25 is not restricted to the exact details of construction disclosed or suggested herein, still for the purpose of illustrating a practical embodiment thereof reference is had to the accompanying drawings, in which like 30 reference characters designate the same parts in the several views, and in which—

Figure 1 is a perspective view showing the means or method of attaching a snow skate to a foot.

35 Fig. 2 is a side elevation of such skate detached.

Fig. 3 is a bottom plan view of the same with both lacing cords loosely connected thereto; and

40 Fig. 4 is a perspective view of a different design of skate with the same arrangement of lacing cords as shown in Figs. 1 and 3.

Referring now more particularly to the drawings I show a skate which may be of 45 any suitable form, structure, or design provided with at least two transverse holes 10 and 11 through the body or runner 12 thereof. A flexible lacer 13 indicated as in the nature of a medium weight, but strong cord

50 or rope, is laced through the hole 10, and through the hole 11 is passed an endless loop shaped cord 14, the length of which is such as to bring the upper portion thereof just above the heel counter C and with a moderate degree of looseness, when the heel of the 55 shoe is in place directly over that portion of

the skate having the hole 11. With the toe of the shoe directly over that portion of the skate having the hole 10, the end or side portions of the lacer 13 are brought directly 60 over the toe and given a half hitch at 15 and thence are extended back and passed inwardly around the side portions of the loop 14, the ends of the lacer 13 coming thence forward and across the instep where they 65 are tied in any easy convenient manner and without any attempt at tightness. A tightener 16 in the form of a short straight flat pin is then passed between the two side portions of the lacer 13 just back of the point 15 70 and thereby the two side portions aforesaid are twisted as indicated at 17 with the result that the lacer 13 will be tightened throughout all its portions and simultaneously with such tightening the loop 14 will be drawn 75 snugly forward over the heel. The pin 16 will then be left in position as indicated, constituting a reliable lock for the fastener. The fastening means indicated insures that the skate will be held firmly from movement 80 in any direction with respect to the foot. Moreover it is exceedingly easy and comfortable for the foot and cannot under ordinary circumstances become accidentally loosened. There is rather a tendency for the 85 cord to tighten due to the moistening of the lacers from the snow and ice.

The form of skate 12 is one that I have practised very successfully and comprises a straight runner portion rectangular in cross section, and having an upturned toe portion 12'. This body is made of wood and faced or bound by means of a strip of strap metal 18 extending from the top of the toe forward, downward, and rearward to the upper 90 surface of the heel portion. For traveling or skating over snow this type of skate is very satisfactory and rapid. In Fig. 4 the type of skate 12^a is likewise made of wood faced with strap metal, and otherwise may 100 be of the same character just described, but having broadened ball and heel portions 12^b and 12^c.

I claim:

1. In a skate, the combination of a body 105 having transverse holes through the toe and heel portions thereof, a long loose ended lacer passed through the hole at the toe, a loop-shaped flexible member passing through the hole at the heel and adapted to extend 110 around the back portion of the foot above the heel counter, said ends of the loose end-

- ed lacer being brought over the toe, crossed and thence extended rearward along the sides of the foot engaging with the loop member and thence brought forward and tied over the instep, and a member acting then upon the side portions of the loose ended fastener to tighten the same and coincidentally tighten the loop member, substantially as set forth.
- 10 2. The combination with a skate body having transverse holes through the toe and heel portions thereof, an endless loop member secured in the hole at the heel and adapted to extend loosely up over the heel counter, 15 a longer loose ended flexible lacer passing through the hole at the toe, the ends thereof being brought up over the toe of the foot, crossed and thence extended rearward around the side portions of the loop mem-

ber and thence forward and fastened across 20 the instep, and a rigid member passing between the side portions of the longer lacer serving to twist the same together tightening both the lacer and loop members simultaneously and serving to hold the fastening 25 means in practice, substantially as set forth.

3. The combination with a skate having transverse openings therethrough, of flexible cord fastening means to secure the same to the foot, said fastening means comprising one endless member of fixed length fitted permanently in one of said openings, and another flexible cord member having loose ends adapted to pass through the other of said openings and coöperating with the endless loop member and rigid means serving to tighten both members simultaneously.

WILLIAM A. ERICKSEN.
